UNITED STATES PATENT OFFICE.

HARRY A. DOUGLAS, OF BRONSON, MICHIGAN, ASSIGNOR TO DOUGLAS & RUDD MFG. CO.,
OF BRONSON, MICHIGAN, A CORPORATION OF MICHIGAN.

REFLECTING-LAMP.

1,261,786.

Specification of Letters Patent. Patented Apr. 9, 1918.

Application filed February 19, 1917. Serial No. 149,667.

To all whom it may concern:

Be it known that I, HARRY A. DOUGLAS, a citizen of the United States, residing at Bronson, in the county of Branch and State 5 of Michigan, have invented a certain new and useful Improvement in Reflecting-Lamps, of which the following is a full, clear, concise, and exact description.

My invention relates to reflecting lamps 10 and has a number of objects and advantages in view. In my invention there are included a holder, preferably in the form of a shell, and a lamp bulb or light source held thereby. My invention is of particular service 15 in connection with electric lamps, and affords an improved means for effecting its assembly and enabling its adjustment.

I will explain my invention more fully by reference to the accompanying drawing 20 showing the preferred embodiment thereof and in which Figure 1 is a side elevation partially in section of a reflecting lamp containing features of my invention; Fig. 2 is a longitudinal view partially in section and 25 partially in elevation of portions of the structure illustrated in Fig. 1; Fig. 3 is a view on line 3-3 of Fig. 4; and Fig. 4 is a view on line 4-4 of Fig. 3.

Like parts are indicated by similar characters of reference throughout the different figures.

The concave reflector 1 is received in the concave casing 2 and is coupled therewith in any suitable way, space intervening between 35 the reflector and casing. The reflector includes a rearwardly extending tubular continuation 3 in fixed relation with the balance of the reflector, this continuation constituting a holder or mounting that is in the form of 40 a tubular neck. A spring tongue 4 presses transversely of and upon said neck and is preferably integrally formed with a shell 5 that constitutes a holder for contact carriers, this spring tongue having ample clearance at 45 its side margins to permit it freely to function. Some part of the tongue, preferably the rear free end thereof, has a part 6 projecting therefrom which is narrower than the balance of the tongue and is slightly narrower 50 than a slot 7 in the neck 3 whereby this portion may project into the slot to prevent the shell from turning with respect to the slot while at the same time the side margins of the tongue 4 are adapted to press against 55 the side margins of the slot 7. The tongue

thus presses upon a surface of the neck 3 and, where there is but one tongue, forces the shell toward the opposite side of the neck whereby the shell is held in engagement with the neck 3. The slot 7 is elongated so 60 that the shell 5 may be moved back and forth in its holding neck 3 whereby in the structure illustrated, the position of the lamp bulb 8 which is carried at the forward end of the shell in front of the reflector may be 65 adjusted with respect to the reflector. The base 9 of the lamp bulb 8 constitutes the forward contact carrier and as the arrangement illustrated is a double pole arrangement this contact carrier 9 carries two rear contacts 10 and 11. The lamp base or contact carrier 9 is provided with bayonet pins (of which one 12 is shown) engageable within bayonet seats (of which one 13 is shown) 70 constituting parts of bayonet slots (of which one 14 is shown). The rear contact carrying plug 15 is provided with terminal blocks 16 having binding screws 17 by which circuit wires may be secured to the terminal blocks. These terminal blocks are 75 desirably cylindrical and the forward ends thereof are desirably tubular, springs (of which one 18 is shown) being included in the tubular portions of the terminal blocks and operating to press contacts 19 80 forwardly into engagement with the contacts 10 and 11. The springs 18 and the contacts 19 and 20 thus not only serve to establish circuit for the lamp but also operate to hold the lamp base 9 in bayonet pin 90 and slot connection with the shell 5. The shell 5 and all of the parts within it are in front of the casing 2 and in order that the shell may be moved in and out I attach a rod 21 to the shell 5 preferably by anchoring the rod within the plug 15 by means of a pin 22. This rod is accessible upon the exterior of the casing for the purpose of moving it back and forth or longitudinally whereby the shell and the lamp bulb carried 95 thereby are correspondingly moved. The rear end of the rod 21 is threaded and has threaded engagement with a sleeve 23 that has an external head 24 engaging the exterior of the casing and which is surrounded by a washer 25 that engages the interior of the casing whereby said sleeve is confined to a single plane of rotation and is prevented from moving back and forth. The head 24 is provided with a screw driver slot 26 100 105 110

(in which a coin may be inserted) whereby the sleeve may be turned and as the sleeve cannot move back and forth the rod 21 must be moved back and forth whenever the sleeve 5 is turned. By this arrangement the lamp 8 is moved in and out to secure any desired relation to the reflector. The spring 4 permits the longitudinal movement of the shell and as its pressure is comparatively heavy 10 it holds the shell in any position to which it may be adjusted.

Any suitable means may be employed for establishing circuit relation between the contacts upon the plug 15 and the external 15 source of current, there being illustrated the well known form of connector 15¹ which may be employed for this purpose.

While I have herein shown and particularly described the preferred embodiment 20 of my invention I do not wish to be limited to the precise details of construction shown as changes may readily be made without departing from the spirit of my invention, but having thus described my invention I claim 25 as new and desire to secure by Letters Patent the following:—

1. In a reflecting lamp, the combination with a light source; of a light source holder, a concave reflector having a neck containing 30 the aforesaid holder; and a spring tongue carried by said holder and exerting pressure transversely of and upon the neck and holder to maintain them in assembly.

2. In a reflecting lamp, the combination 35 with a light source; of a light source holder movable in and out; a concave reflector having a neck containing the aforesaid holder; and a spring tongue carried by said holder and exerting pressure transversely of and 40 upon the neck and holder to maintain them in assembly, the neck having a slot into which a portion of the spring tongue projects, the slot being elongated to permit the light source holder to move in and out.

3. In a reflecting lamp, the combination 45 with a light source; of a light source holder; a concave reflector having a neck containing the aforesaid holder; and a spring tongue carried by said holder, the neck having a slot 50 into which a portion of the spring tongue projects, side portions of said tongue pressing transversely of the neck and holder upon portions margining said slot to maintain the neck and holder in assembly.

55 4. In a reflecting lamp, the combination with a light source; of a light source holder

movable in and out; a concave reflector having a neck containing the aforesaid holder; and a spring tongue carried by said holder, the neck having a slot in which the spring tongue projects, side parts of said tongue pressing transversely of the holders upon portions margining said slot to maintain the neck and holder in assembly, the slot being elongated to permit the light source 60 holder to move in and out.

5. In a reflecting lamp, the combination with a light source; of a light source holder movable in and out; a concave reflector having a neck containing the aforesaid holder; a spring tongue carried by said holder and exerting pressure transversely of and upon the neck and holder to maintain them in assembly, the neck having a slot into which a portion of the spring tongue projects, the slot being elongated to permit the light source 70 holder to move in and out; and a rod connected with the light source holder and operable from the exterior of the lamp to move this holder in and out.

6. In a reflecting lamp, the combination with a light source; of a light source holder movable in and out; a concave reflector having a neck containing the aforesaid holder; a spring tongue carried by said holder, the 85 neck having a slot into which a portion of the spring tongue projects, side parts of said tongue pressing transversely of the neck and holder upon portions margining said slot to maintain the neck and holder in assembly; and a rod connected with the light source holder and operable from the exterior of the lamp to move said holder in and out.

7. In a reflecting lamp, the combination with a light source; of a light source holder movable in and out; a concave reflector having a neck containing the aforesaid holder; a spring tongue carried by said holder, the neck having a slot in which the spring tongue projects, side parts of said tongue 100 pressing transversely of the neck and holder upon portions margining said slot to maintain the neck and holder in assembly, the slot being elongated to permit the light source holder to move in and out; and a rod 105 connected with the light source holder and operable from the exterior of the lamp to move said holder in and out.

In witness whereof, I hereunto subscribe my name this 24th day of January, A. D. 116 1917.

HARRY A. DOUGLAS.
